UNITED STATES PATENT OFFICE

JOSEPH B. FORD, OF CHICAGO, ILLINOIS

GOLF GAME

Application filed November 12, 1930. Serial No. 495,008.

My invention relates to a game which is adapted to be played with golf balls and clubs and in which a novel type of putting green is provided.

5 The principal object of my invention is the provision of a new game.

Another object is the provision of a golf game having novel features, both as to method of play and construction of the apparatus.

10 Another object is a new game adapted to be played with golf apparatus, but which may be scored in accordance with the rules of a standard card game.

15 Another object is the provision of an improved game board.

Other objects and features of the invention will be apparent from a consideration of the following detailed description taken 20 with the accompanying drawing, wherein

Fig. 1 is a plan view of the putting apparatus on which the game is adapted to be played,

25 Fig. 2 is a fragmentary longitudinal sectional view, shown slightly larger than Fig. 1,

Fig. 3 is an enlarged plan view partly broken away, showing features of construction, and

30 Fig. 4 is a perspective view showing the putting position.

In the construction shown, the approaching green 10 and horizontal putting green 11, are formed integral and comprise a suitable sub-frame work, including cross-members 12 and flooring 13. The cross-members 12 gradually decrease in height along the approaching green until at the putting position the floor 13 is substantially in line 35 with the floor of the room in which the apparatus is mounted. Around the horizontal putting area I provide sideboards 14, spaced from the putting surface by gutter boards 16, which extend below the surface of the floor 13. This provides a gutter around 40 three sides of the space 11 into which the golf balls are adapted to roll, if putted hard enough to pass completely over the space 11, or if they are off-direction. At the top of 45 the sideboards 14 I provide a spacer 17 to

which is secured in pendant relation thereto a curtain 18 of resilient material, such as semi-soft rubber, this curtain extending almost to the bottom of the gutter. This curtain functions positively to trap any ball in 55 the gutter, which strikes against it, so that there is no possibility of a ball striking the sideboards 14 and bounding back onto the scoring or counting green.

The floor 13 is covered with suitable material throughout to serve as a putting surface to approach as near as possible the conditions existing in an ordinary golf putting green. This putting surface is divided into three sections; namely, the section on the approaching green 10, a scoring green 19, and a non-scoring green 21. While these sections may all consist of the same material or type of material, for the proper functioning of the apparatus as a whole, I 60 prefer to have each section slightly different than each other section. The approaching green should allow a ball to move smoothly, but should be sufficiently fast so that if the player does not putt true and straight, or 65 if he does not putt a sufficient distance, the ball will have a tendency to roll off of such surface, with a stroke penalty. The non-scoring green section 21 should be smooth 70 and allow a ball to move over the same 75 readily, but preferably should be somewhat slower. The section 19 should be medium fast to secure the best playing results.

As to the specific materials used, I may 80 employ special grades of rubber matting, carpet of suitable texture, molded compositions or the like. If desired, I may use the same type of material throughout the entire putting surface. The materials used in the frame-work portions of the device may be 85 modified, but in general I would prefer to employ wood throughout except for the floor portion 13, which may be made of a material such as Celotex, which is light in weight, sufficiently strong, possessed of 90 smoothness, with no tendency to warping, and which has a sound deadening effect. However, other types of materials may be 95 used instead of Celotex.

In my preferred embodiment I mark the 100

scoring green 19 out in squares as shown, each square corresponding to one ordinary playing card, and there being 52 squares so that each card in a standard deck may be represented. I may, however, use only a limited number of squares and so not use all of the cards of the standard deck or the squares may be marked with different indicia depending upon the specific manner 10 in which the game is to be played.

Fig. 3 shows the squares marked up to represent cards, the denomination of the card being indicated by a letter or figure and the suit being designated by the first 15 letter of the suit which the card represents. For example, "KS" would represent the king of spades and "3C" would represent the three of clubs. This showing is made for convenience, it being understood that 20 other ways of showing the card, such as the conventional card faces, or entirely different indicia may be employed.

Near the lower end of the approaching green I provide means for supporting golf 25 balls, this means constituting the putting position from which the balls are to be putted. In the particular form shown, a flat ball retaining troughlike ledge 22 is provided, which serves as a teeing position. A smooth approach, however, is made 30 to the approaching green proper so that there will be no tendency for the balls to bounce when played off of the putting position. This flat construction extends 35 entirely across the approaching green so that the player may play from any position selected by him. However, in playing the game rules may be provided that the player must putt from the exact center.

40 As to the manner in which the game is played, a number of balls are putted from the putting position, using an ordinary golf putter and the balls score according to the position on the scoring green in which they 45 stop. For example, five balls may be putted by each player, and a poker hand may be made, corresponding to the cards indicated by the squares in which the balls are stopped. If desired, the players may 50 "draw" as in an ordinary game of draw poker. For example, if a player had a pair of kings and three worthless cards, he could elect to putt three more balls, with the idea of improving his hand. When a ball stops 55 on the space 21, the player may have the privilege of playing another ball for the one stopping at such position, or if desired he may be permitted to putt again from the position on the space 21 on which his ball 60 stopped. A ball stopping in the gutter, however, would be a dead ball and would not count. This is merely illustrative, as it is obvious that many types of card games could be played. The game known as 65 "blackjack" or "twenty-one" is an example

of a game which can be played as readily as poker. In this way the players not only have the skill of putting, which is tested by the game, but in addition have the attraction of attempting to score as good a card 70 hand as possible. Since it is almost impossible to putt with such accuracy as to pick out cards before putting, there is an element of luck in the game equivalent to the luck of the deal in an ordinary card 75 game.

While the game may be constructed in substantially any size, I have found the best results when the squares representing the 80 cards measure approximately seven inches each way, and in which the approaching green is approximately fifteen feet in length from the putting position to the scoring position. These dimensions are illustrative, however, and may be changed.

Although I have described my invention in detail so that those skilled in the art may practice the same, it is obvious that I am not restricted to the particular form of apparatus and that the invention is limited 90 only by the scope of the appended claim.

I claim:

In a golf game, a platform having a center scoring green divided into a plurality of scoring squares and formed of material 95 over which a golf ball will roll relatively freely, a non-scoring green surrounding the scoring green formed of material over which the progress of the ball is relatively "slow", and a relatively long inclined approaching 100 green formed of material over which a ball will roll relatively freely, whereby the ball may be putted from a putting position on the approaching green onto the platform, and whereby, if the ball does not reach the 105 platform, it will roll back to the putting position.

In witness whereof, I hereunto subscribe my name this 25th day of October, 1930.
